UNITED STATES PATENT OFFICE.

ALLEN A. TIRRILL, OF ATHENS, PENNSYLVANIA.

ELECTRIC SWITCH.

1,161,362.

Specification of Letters Patent. Patented Nov. 23, 1915.

Application filed June 24, 1910. Serial No. 568,747.

To all whom it may concern:

Be it known that I, ALLEN A. TIRRILL, a citizen of the United States, residing at Athens, in the county of Bradford and State of Pennsylvania, have invented certain new and useful Improvements in Electric Switches, of which the following is a specification, reference being had therein to the accompanying drawing.

10 This invention relates to improvements in electric snap switches primarily designed for use in connection with lighting circuits, though capable of use in other connections, and has for its primary object improvements of that general type of switch set forth in my copending application, Serial No. 525,226, filed October 28, 1909.

20 The present invention comprehends the provision of improved contacts, and mountings therefor, the latter eliminating to a substantial extent the danger of arcing between the relatively movable and stationary contact members, an improved arrangement of contacts and circuits enabling the production of what may be termed a two-circuit-selective-type of switch; and improved details in the construction and arrangements of parts, all as will more fully hereinafter appear.

30 To enable a complete understanding of the invention, I have illustrated in the accompanying drawings, forming part hereof, a two-circuit type of switch constituting a convenient embodiment of the invention.

35 The construction and operation of the same will be clear from an inspection of said drawings in connection with the detailed description hereinafter contained.

40 It will also be apparent to those skilled in the art that the improvements are capable of embodiment in types of switches other than that illustrated herein, for instance, in a single-pole, a double-pole, or a three-way switch.

45 Referring more specifically to the drawings: Figure 1 is a bottom view of the switch with the cover or cap removed, Fig. 2 is a vertical longitudinal sectional view showing the cap or cover in place, Fig. 3 is a side view, portions of the cover being broken away, Fig. 4 is an opposite side view, the cover being entirely removed, Fig. 5 is a detail perspective view of one of the combined binding posts and contact devices removed, Fig. 6 is a perspective view of the main supporting standard or bracket re-

moved, Fig. 7 is a perspective view of the rotatable operating member or sheave removed, Fig. 8 is a perspective view of the indicator removed, Fig. 9 is a transverse section illustrating the manner of securing the indicator in place, Figs. 10 and 10^a are sectional views through the movable contact member of the switch illustrating especially the insulating elements, and Figs. 11, 12, 13 and 14 are diagrammatic views indicative of the various positions of the switch, and the corresponding condition of the circuits and lamps controlled thereby.

50 Referring more specifically to the drawings, wherein like reference characters designate corresponding parts in the several views, C represents a porcelain or other suitable base of insulating material. Secured by means of screws d to the base C and suitably spaced apart are brackets D, D' conveniently formed of sheet metal, apertured for the accommodation of and to serve as bearings for a switch blade-carrying shaft E. The end portion of the shaft 70 E is of angular cross-section, represented at e adjoining a shoulder e' to prevent turning of the switch-blades relative to the shaft. The extreme end of said shaft is grooved, as at e² for the reception of a split washer F 75 fastened in place by pinching the ends thereof together (Fig. 4).

80 The switch-blades G are mounted intermediate of the shoulder e' and the washer F, a substantial space being provided therebetween to enable the switch-blades to freely shift laterally (longitudinally of the shaft) whereby to be self-aligning with reference to their co-operating contact members. This subject-matter is broadly set forth in my 85 said copending application Serial Number 525,226, filed October 28, 1909.

90 The switch blades are formed of two pieces of sheet spring metal each of which comprises a hub or central portion G' and three arms g extending outwardly therefrom, which are off set slightly from the plane of said central portion. In assembling the switch blades, the two pieces of sheet 95 spring metal are arranged with the hubs or central portions G' in juxtaposition so that the arms g projecting therefrom constitute three pairs of spring contacts. The arms g are slotted longitudinally, as at g', to give greater flexibility thereto and are connected 100 at the ends to shoes g², the outer ends of which are flared outwardly to readily per-

mit the passage between the shoes of each pair of arms of a stationary contact member upon rotation of the switch blades, as is well known in this art. The hub or central portion G' of each of the metal plates of the switch blades is elongated, and substantially elliptical in shape and the arms g project from the long sides of said hub or central portion, the longitudinal or center lines of 5 each of said arms being positioned at an angle or about 45 degrees to the periphery of the hub or central portion G' , so that there is provided for each of said arms an inclined supporting portion. This arrangement 10 allows the greatest possible amount of clearance between the central portions G' of the blade members and the stationary contacts when the blades are revolved, more especially when the contact portions of the 15 blade leave the stationary contacts, thus preventing arcing. It will also be seen that inasmuch as each of the arms carrying the contact shoes is mounted on an inclined supporting portion, a broad, firm mounting is 20 provided for the lower end of said arm.

It is of course desirable that the switch blades be insulated from the shaft E and to that end the interior of the central or hub portions G' of the sheet metal plates forming the blades are cut away, as at g^3 , for the reception of the intermediate member of the insulation g^4 which is provided with a central opening for the reception of the shaft E . The insulation is preferably arranged 30 in sheets, an intermediate sheet which fits the openings in the central portion of the blade members g' , and an outer sheet of a size to overlie the opposite faces of said intermediate sheet and the adjacent portions 35 of the sheet metal members of the plate G . The outer sheets of the insulation are arranged between the outer surfaces of the sheet metal members of the blade G and approximately elliptical shaped plates H on 40 the outside thereof, the parts being connected by means of rivets h which pass through the plates H and the interposed insulation.

The combined binding posts and stationary contacts I are three in number, corresponding to the arms of the switch blades or 50 clips, each having a base i fastened at two points by screws i' to the base C and having a binding screw i^2 adjoining a lug i^3 arranged adjacent to an aperture c in the base 55 C for the passage of the wire terminal. The outer devices I , have upwardly extending arms J having inwardly projecting curved contact ends J' shaped to correspond to an arc of the circle of rotation of the switch 60 blades whereby to be received between the switch blades and contact therewith, as is obvious. The intermediate stationary contact I is of substantially the same general formation, the supporting arm J^2 , however, 65 in this instance being relatively short and

the curved contact J^3 arranged near the base C of the switch, thus placing all the stationary contacts in the same circle of rotation of the switch, as is clearly shown in Fig. 4.

The means for effecting the quick or snap action of the switch will now be described. Mounted loosely upon the shaft E is a sheave L carrying a bushing projecting axially therefrom and surrounding said shaft. The sheave L is formed of sheet metal plates 75 l brought together to form a rigid central portion or web l' , sleeved upon the shaft E , portions of the margins of the plates being curved outwardly to together form a cord or chain groove l^2 near one end of which the 80 plates are perforated transversely as at m and bent outwardly at its edges, as at m' , to form a slot M for the introduction of an off set T -head n of a detachable connecting device N , carried at the end of a pull chain or cord L' (Fig. 3) adapted to be suspended from the switch for operating the sheave and the switch blades through the medium of said sheave. The cord L' may be of any well known type and such cord may, if desired, be connected to the sheave, in any suitable manner other than above described.

The standard D formed of sheet metal, as illustrated, has an off set flange d' at one side thereof projecting over the peripheral portion of the sheave (Fig. 3) and arranged in close proximity thereto to prevent the escape of the chain or cord from the sheave. Below this retaining flange and disposed at approximately right angles thereto, another flange d^2 , carrying a bushing or guiding eye d^3 serves as an additional retainer, and constantly maintains the cord or chain in operative position. The bushing d^3 projects through an aperture in the switch cap or 100 cover S , as shown, and a threaded flange s' , also on the standard D , co-operating with a screw s passing through the cap, centers and secures the cap in place. The cap s is conveniently provided with a lining of insulation. 110

To limit the rotation of the sheave L in both directions, a stop lug l^5 (Figs. 3 and 7) is struck outwardly from the outermost plate forming the sheave, so that it projects 115 into a curved slot l^4 of the standard D , said stop lug being arranged to abut the end walls of this slot at the termination of its movement in opposite directions incident to the rotation of the sheave. The sheave normally occupies the position shown in Fig. 3 with the stop lug l^5 in engagement with the rear end wall of the slot l^4 in the standard D , this position being maintained by means of a spring R , one end of which is connected in any suitable manner to the upright D and the other end of which abuts an offset tail piece u of a pawl U which projects through an opening l^6 in the sheave L said pawl being arranged on the opposite side of 125 130

the sheave and pivoted thereto as at u' . The pawl U engages a ratchet disk V, which is loosely mounted on the shaft E and the function of the spring R is not only to hold the shaft in the position shown in Fig. 3, and to return the same to such position when moved therefrom, as will hereinafter appear, but also incident to the engagement of the end of such spring with the tail piece u of the pawl U, to normally hold said pawl in engagement with a tooth of the ratchet disk V. What I will term the motor spring, is shown at O, one end of such spring being engaged with the ratchet disk V and the other end of such spring bearing against an off set lug p^2 of a detent carrier P' fixed to the shaft and normally held against rotation under force of the motor spring because of the engagement of the detent P'; carried by such detent carrier with one of the stop shoulders q of a fixed disk Q which is rigidly secured in any suitable manner to the upright D'. Normally the detent P' is retained in engagement with the shoulder q , just referred to, by means of a cam plate Q' having the slot q through which a lug p^3 off-set from the detent P', projects, the cam plate being in turn held against excessive movement in either direction by means of shoulders q^2 adapted to abut the off set lug p^2 of the detent carrier before referred to. The operation of the mechanism thus far described may now be followed.

Assuming the parts to be in the position indicated in the several views of the drawings, a pull upon the cord or chain L will store up power in the motor spring O and by the coöperation of the several devices, permit said motor spring to exercise its energy and rotate the switch plate G with a quick snappy action, to engage or by progressive rotary movement, to alternately engage and disengage with the spring contact devices I. More specifically, the pull upon the cord or chain L' rotates the shaft in the direction of the arrow (Fig. 3) and the pawl U carried therewith engaging one of the teeth of the ratchet V rotates it in the same direction, the rotation of the sheave being of course against the tension of its restoring spring R. This rotation of the ratchet disk V winds up the motor spring O, one end of which spring is connected to the ratchet disk and the other end abutting the fixed lug p^2 of the detent carrier P, which latter cannot move at this time by reason of the engagement of the detent P' with the fixed stop disk at q . The cam plate Q' being connected with the ratchet disk V, rotates therewith and by means of the cam way or groove, q' thereof, engaging with the offset lug p^3 , of the detent, P', gradually elevates the detent out of engagement with the shoulder q , the parts being so proportioned and timed in their operation

that the motor spring O will have the desired power or energy started up therein at the time the detent leaves said shoulder. Practically instantaneous upon the disengagement of the detent P' from the shoulder q , the detent carrier P is released and under the action of the motor spring O in engagement with the offset p^2 thereof, shifts said carrier around one fourth of a revolution, or until the lug p^3 of the detent is guided by the cam way r into engagement with the next adjacent stop shoulder q of the fixed plate Q. The detent carrier P being keyed to the shaft E, rotates said shaft therewith and shifts the switch blades G into or out of engagement with the spring contact devices I as the case may be. After the operation just stated, and upon the release of the cord L', the sheave will be returned under the action of its spring R to its initial position.

The detent carrier P is provided with oppositely arranged ears p formed with the carrier and apertured and threaded as indicated at p' to receive fastening screws 90 passing through similar ears t' projecting inwardly from an indicator drum T (Fig. 8) said drum being also formed of sheet metal with a flat peripheral portion t^2 and an inwardly extending strengthening 95 flange t^3 .

The peripheral portion referred to is differently colored at various portions thereof to indicate through a sight-opening T' (Fig. 2) in the cap or cover S, the different positions of the switch. It will be appreciated that the formation of this indicator is extremely simple, while at the same time strong and readily adapted for use upon the particular type of switch herein disclosed, 105 or other types involving a rotatable part, the hoop construction of the indicator permitting the same to encircle the mechanism while offering no obstruction to the working parts of the mechanism and requiring 110 the provision of substantially no additional space to accommodate the same.

The successive rotations of the sheave, under corresponding-pulling action by the user on the depending cord or chain, will rotate 115 the switch-blades so that the three arms thereof, rigidly held in their right-angular relation, will progressively assume the different positions, relative to the stationary contacts, illustrated diagrammatically in the 120 last four figures of the drawings, and from an examination of these diagrams, the two-circuit-selective character of the switch will be understood. Referring to the first of these diagrams wherein the numerals 1 and 2 represent the lamps, each provided with its own circuit, it will be seen that the switch arms are arranged to bridge the two outer stationary contacts, the intermediate switch arm and the intermediate stationary contact 130

being disconnected so that neither lamp circuit is closed with the electrical supply or feed.

The second diagrammatic view illustrates 5 the position of the switch after the first pull on the cord or chain. Here it will be seen that one of the outer stationary contacts is electrically connected with the intermediate contact, while the opposite outer stationary 10 contact and one arm of the switch are disconnected, whereby a closed circuit is formed through the lamp No. 1, as indicated by the arrows.

The third diagrammatic view illustrates 15 the position of the switch after the second pull on the cord or chain, it being seen that in this instance all three of the switch arms are engaged with the corresponding three stationary contacts and both lamp circuits 20 completed, including the lamps Nos. 1 and 2, as indicated by the arrows.

Upon the third pull of the cord or chain, 25 the switch is shifted to the position indicated in the fourth diagram wherein it will be seen that the intermediate stationary contact is electrically connected with the outer stationary contact opposite to that shown in the second diagram, whereby the circuit of lamp or lamps No. 2 is closed, while the 30 circuit of lamp No. 1 is opened by the disengagement of the third arm of the switch and the opposite outer stationary contact.

A fourth pull on the cord restores the 35 parts to the position shown in the first diagram with both circuits broken.

Conveniently the lamp No. 1 may represent a single light, while the lamp No. 2 may represent several lights, for instance two, or the grouping may be otherwise, as 40 desired.

From the foregoing, the advantages of my improved switch will probably be instantly appreciated. It will be observed that the device enables the choice of two circuits, 45 thus constituting a two-circuit-selective type of switch, as I have previously stated which in many cases, will be found the full equivalent of many three-circuit switches wherein it is customary to have the respective circuits completed successively, one after the other, and finally all cut out simultaneously. In the present instance, it will be seen the first operation will, for example, light one lamp of a three-lamp electrolier, the second 50 operation will light two additional lamps, making the three illuminations, the third operation will cut out the first lamp leaving two illuminations, and the fourth operation extinguishing the two lamps. It will thus 55 be seen that there is the choice of the lighting of one, two or three lamps by the simple manipulation of my improved switch in connection with but two circuits.

The porcelain base C may be provided 60 with any number of grooves in its back in

any desired arrangement, and with any necessary number of wire passages through the base, to enable the coupling up of the switch with the wiring; and the arrangement of the switch blades may be optional, either at 70 one or both ends of the operating shaft, and in any desired operative relation, to provide any particular type of switch, in keeping with the service to which the same is to be put.

While I have herein disclosed one practical embodiment of the invention, it is to be understood that many changes and alterations in the details and arrangements may be made without in the least departing from 80 the spirit of the invention.

I claim:—

1. In a switch of the character described, operating mechanism including a rotatable part and an indicating drum carried thereby, said drum having differentiated indicators on its periphery, said drum being formed of sheet metal and having a wide peripheral portion and a reinforcing side flange.

2. In a switch of the character described, operating mechanism including a rotatable part and an indicating drum carried thereby, said drum having differentiated indicators on its periphery, said drum being 95 formed of sheet metal and having a wide peripheral portion and a wide reinforcing flange, in combination with means engaging said flange and the movable part which carries the drum to detachably secure the latter 100 in place.

3. A switch of the character described comprising a supporting standard, operating mechanism associated with said standard including a rotatable part and provided 105 with an offset lug limiting the movement of said part in opposite directions, the standard being provided with a curved slot, the ends of which are adapted to coöperate with said lug, substantially as described.

4. A switch of the character described comprising a sheet metal supporting standard, switch operating mechanism associated therewith including a rotatable sheave, and a cord or chain attached thereto peripherally engaging the sheave to operate the same, the standard being provided with a laterally bent flange adjacent to the periphery of the sheave to prevent escape of the cord or chain, substantially as described.

5. A switch of the character described comprising a sheet metal supporting standard, switch operating mechanism associated therewith including a rotatable sheave and a cord or chain attached thereto peripherally engaging the sheave to operate the same, the standard being provided with a laterally bent flange at its side adjacent to the periphery of the sheave to prevent escape of the cord or chain, substantially as described.

6. A switch of the character described comprising a supporting standard, switch operating mechanism associated therewith including a rotatable sheave and a cord or 5 chain attached thereto peripherally engaging the sheave to operate the same, the standard being provided with a flange at its side adjacent to the periphery of the sheave to prevent escape of the cord or chain, and 10 another flange on the standard below the side flange apertured to constitute another guide for the cord or chain.
7. A switch of the character described comprising a supporting standard, switch 15 operating mechanism associated therewith including a rotatable sheave, and a cord or chain attached thereto peripherally engaging the sheave to operate the same, the standard being provided with a flange at its 20 side adjacent to the periphery of the sheave to prevent escape of the cord or chain, and another flange on the standard below the side flange apertured to constitute another guide for the cord or chain, the last mentioned guide having a projecting eye, and a 25 cover for the switch mechanism apertured for the reception of said eye.
8. A switch of the character described comprising a standard, operating mechanism associated therewith, a cord or chain 30 for actuating said mechanism, and a cover
- for inclosing the mechanism, the standard being provided with flanges projecting in opposite directions from the opposite edges of the standard, one provided with an eye 35 projecting through an aperture in the cover to constitute a guide for the operating cord or chain, and the other apertured for engagement by a fastening device passed through the cover, substantially as and for 40 the purpose described.
9. An electrical switch comprising a shaft, and a switch member mounted thereon having a hub portion that is elongated transversely of the shaft and a flexible contact 45 arm extending transversely to the major axis of the hub portion.
10. An electrical switch comprising a shaft having a flattened portion, and a switch member mounted thereon having a hub portion that surrounds the flattened portion of the shaft and is elongated transversely of the shaft and a flexible contact arm extending transversely to the major 50 axes of the hub portion and the flattened 55 portion of the shaft.

In testimony whereof I affix my signature in presence of two witnesses.

ALLEN A. TIRRILL.
